(57) **CLAIM**

We claim the ornamental design for a cutting tool, as shown and described.

DESCRIPTION

FIG. 1 is a perspective view of an embodiment of the claimed design;

FIG. 2 is a top view of the claimed design of FIG. 1;
FIG. 3 is a bottom view of the claimed design of FIG. 1;
FIG. 4 is a right side view of the claimed design of FIG. 1;
FIG. 5 is a left side view of the claimed design of FIG. 1;
FIG. 6 is a front view of the claimed design of FIG. 1;
FIG. 7 is a rear view of the claimed design of FIG. 1;
FIG. 8 is a perspective view of another embodiment of the claimed design;

FIG. 9 is a top view of the claimed design of FIG. 8;
FIG. 10 is a bottom view of the claimed design of FIG. 8;
FIG. 11 is a right side view of the claimed design of FIG. 8;
FIG. 12 is a left side view of the claimed design of FIG. 8;
FIG. 13 is a front view of the claimed design of FIG. 8; and,
FIG. 14 is a rear view of the claimed design of FIG. 8.

The ornamental design which is claimed is shown in solid lines in the drawings. The broken lines in the drawings are for illustrative purposes only and form no part of the claimed design.

The broken line showing of the cutting tool is included for the purpose of illustrating portions of the article and forms no part of the claimed design.
